CLAIM

The ornamental design for a microbiological culture container, as shown and described.

DESCRIPTION

FIG. 1 is a perspective view of a microbiological culture container in assembled condition, showing my new design;

FIG. 2 is an exploded perspective view thereof, with the container in disassembled condition;

FIG. 3 is a front elevational view thereof, as shown in FIG. 1; and

FIG. 4 is a bottom plan view thereof.

FIG 1

FIG 2
